CLAIM

The ornamental design for a carpet shampooer, as shown and described.

DESCRIPTION

FIG. 1 is a front, left, and top perspective view of a carpet shampooer, showing my new design;
FIG. 2 is a rear, right, and bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view taken from the encircled portion labeled "9" in FIG. 2.

The dot dash broken lines in FIGS. 2 and 9 denote the boundaries of the enlarged area and form no part of the claimed design. The dash broken lines in the drawings depict portions of the carpet shampooer that form no part of the claimed design.

1 Claim, 9 Drawing Sheets
